WIRE SOAP HOLDER

Isidore Morse, Bronx, N. Y.

Application September 28, 1949, Serial No. 5,201

Term of patent 7 years

(Cl. D4—3)

To all whom it may concern:

Be it known that I, Isidore Morse, a citizen of the United States, residing at the Bronx, New York, in the county of Bronx and State of New York, have invented a new, original, and ornamental Design for a Wire Soap Holder, of which the following is a specification, reference being had to the accompanying drawing, forming part thereof.

In the drawing:

Fig. 1 is a top plan view of a wire soap holder, showing my new design;

Fig. 2 is a front elevational view of the same; and

Fig. 3 is a side elevational view of the wire soap holder.

I claim:

The ornamental design for a wire soap holder, as shown.

ISIDORE MORSE.
